UNITED STATES PATENT OFFICE.

THOMAS ARMAT, OF RICHMOND, VIRGINIA.

CAR-COUPING.

SPECIFICATION forming part of Letters Patent No. 361,664, dated April 26, 1887.

Application filed January 13, 1887. Serial No. 224,276. (No model.)

To all whom it may concern:

Be it known that I, THOMAS ARMAT, a citizen of the United States, residing at Richmond, in the county of Henrico and State of Virginia, have invented a new and useful Improvement in Car-Couplings, of which the following is a specification.

My invention relates to improvements in car-couplings; and it consists in a certain novel construction and arrangement of parts for service, fully set forth hereinafter, and specifically pointed out in the claims.

In the accompanying drawings, Figure 1 is a side view of two cars provided with my improved coupling, as seen when coupled together. Fig. 2 is a bottom plan view of the same. Fig. 3 is a vertical longitudinal section of my improved coupling on the line $x-x$ of Fig. 2. Fig. 4 is a front elevation of one of the cars.

Referring to the drawings, in which similar letters denote corresponding parts in all the figures, A represents the draw-head having the flared opening or mouth B, the upper and rear side of which opening being curved down to meet the horizontal bottom of the opening at the point b. C is a block bolted to the bottom of the said opening and having a beveled front side, c, and a beveled rear side, c', the rear side being also curved in plan, for a purpose hereinafter explained. The said draw-head is sustained under the front part of the car by the guide or sleeve D, in which the draw-head is adapted to slide.

To the rear side of the draw-head A are bolted the front bent ends of the side braces or cleats, E, between the rear ends of which is bolted the front end of the heavy bar F, which is adapted to slide in ways or guides G G', and has a rigid collar or projection, H, between said ways or guides to limit the motion of the said bar F. The rear end of the bar F, beyond the guide G', is secured to the front side of an elliptical spring, I, the rear side of which is secured rigidly to the bottom of the car. Therefore it will be seen that any heavy body, as a car, coming against the end of the draw-head, will force it in under the car against the action of the powerful spring I; but said spring being very strong, will receive and entirely deaden the shock caused by the contact. The sliding buffers K K', on either side of the draw-head,

are also provided with elliptical springs k k', arranged in the same manner as the spring I, to receive and aid in deadening the shock of meeting cars.

L represents a sliding bolt having a square front end, and adapted to operate in a horizontal opening, M, in the rear side of the draw-head, said bolt being arranged to pass for a short distance over the top of the beveled block C, and very close thereto, the forward motion of said bolt being limited by a pin, l, in the rear of the draw-head. Between the said braces E, a short distance in rear of the draw-head, is fixed a cross-plate, N, provided with an opening, n, through which passes the rear end of a stud, O, rigidly secured in the rear end of the bolt L, and on said stud O, and bearing respectively against the plate N around the opening therein and the rear end of the bolt L, is fixed a spiral spring, P, the tendency of which is to normally hold the bolt L pressed forward over the rear side of the block C.

Q is a rope or chain secured to the rear end of the stud O and passes around a pulley, R, some distance in rear of the said stud, and then forward to the front part of the platform, where, after passing around a pulley, R', it is secured to a lever, S, which is journaled some distance below the car on a depending standard, S'. The said lever S is carried some distance above the floor of the car or platform and adapted to be operated to draw back the bolt L, Fig. 4 showing, in dotted lines, the position of the lever when said bolt is drawn back. The motion of the lever in the opposite direction is limited by the pin or stud s; and it will be seen that when the lever is swung down to draw back the bolt the spring P will be contracted, and when the lever is released the bolt will be returned to its normal position and the lever will also be drawn up to the position shown in solid lines in Fig. 4.

When it is desired to couple two cars having my improved coupler, the cars are caused to approach each other, one having the coupling-link T held out horizontally from the draw-head. When the front end of the said link reaches the opposite draw-head, it is raised by sliding up over the front beveled side of the block C, presses back the bolt L, and drops behind the said block, while the bolt springs

75

100

out over the link and locks it behind the said block. If the approaching car having the link is higher than the other car, the front end of the link will enter the draw-head at the 5 top, and, sliding down, (guided by the downwardly-curved top of the said draw-head,) will press the bolt back, and still be guided down until it clears the front end of the bolt, when said bolt will spring out over the link and 10 lock it in place.

It will be seen that, as the rear side of the 15 block C is curved, the link is enabled to have a firm hold, and as it is impossible for the link to become disengaged from the block (as to do this it would be necessary to press back the bolt L, which is securely maintained in position by the spring P) my coupling is perfectly safe and strong.

To uncouple the cars, swing the lever in the 20 direction indicated by the arrow in Fig. 4, and the bolt L will be drawn back against the action of the spring P by the rope or chain acting around the pulleys, and the link will be free, it requiring but a slight pull upon the 25 link to cause it to slide up over the beveled rear side of the block C and pass out of the draw-head. This uncoupling action is completed in a moment. As there is always a pull exerted on the coupling-link, the moment the 30 lever is pressed down and the bolt or latch L retracted the link will pass out of the draw-head, and the lever being immediately released, the bolt will return to its normal position and the coupling is in position to form another 35 connection. A coupling is also made in an instant, for the link, guided by the block C or the top of the draw-head, is caused to act directly on the latch or bolt L, and as soon as said bolt is driven back the link passes behind the block and is secured there by the latch returning to its normal position.

It will be seen that the action is very direct, 40 the means employed are very simple, and the result attained is very satisfactory. There is no complication of devices which is easily put 45 out of order and with difficulty repaired, and especially does my coupling device have an advantage over similar devices now in general use, in that the lever S is the only part of the 50 mechanism which is visible from the platform of the car, it being of special advantage to preserve the platform as free from the coupling and uncoupling mechanism as possible.

It will be observed that the action both in 55 coupling and uncoupling is entirely under the car and out of the way, said action being further limited to a very small space under the car.

The means which I employ for breaking or 60 deadening the shock of coupling cars are also very simple, yet strong and reliable.

Having thus described my invention, what I claim, and desire to secure by Letters Patent of the United States, is—

1. In a car-coupling, the draw-head adapted 65 to slide in a guide or sleeve and joined to the front end of the bar F, adapted to slide in guides G G', and having the collar H, to limit the forward and backward motion of the said bar, combined with the elliptical spring I, to receive the shock on the outer end of the draw-head, substantially as described, for the purpose set forth.

2. In a car-coupling, the draw-head having 70 an opening therein, combined with a latch moving in a horizontal opening in the rear side of the draw-head and having a rearwardly-projecting stud provided with a spiral spring to press respectively against the rear side of the said latch and a plate, N, provided with an 75 opening through which the rear end of the said stud projects, substantially as described, for the purpose set forth.

3. In a car-coupling, the draw-head having 80 a flared opening, the upper side of which is curved downwardly to meet the bottom, and the block beveled on the front side, combined with the spring-actuated latch to be pushed back by the engaging-link and adapted to spring over the link when it drops behind the 85 said block and hold it in engagement therewith, substantially as described, for the purpose set forth.

4. In a car-coupling, the draw-head having 90 an opening therein and the beveled block, 95 combined with the spring-actuated latch to be normally held protruded over the top of the said block, substantially as described, for the purpose set forth.

5. In a car-coupling, the draw-head having 100 an opening therein, the block beveled on the front side, and the spring-actuated latch, combined with the chain secured at one end to the said latch and passing around the pulleys R R', secured at the other end to the lever S, said lever being adapted to be pressed to one side to draw upon the said chain and retract the latch, substantially as described, for the purpose set forth.

6. In a car-coupling, the draw-head having 105 a flared mouth and an opening with the upper side downwardly curved to meet the lower side, and the block beveled on front and rear sides, combined with the spring-actuated latch or bolt to secure the link in engagement with the rear side of the block and adapted when drawn back to release the link and allow it to be drawn out of engagement with the said block by sliding over the beveled rear side thereof, substantially as described, for the purpose set forth.

In testimony that I claim the foregoing as my own I have hereto affixed my signature in presence of two witnesses.

THOMAS ARMAT.
